Assistant Examiner—Mark Goodwin

(74) **Attorney, Agent, or Firm**—Foley & Lardner LLP

(57) **CLAIM**

We claim the ornamental design for a knob, as shown and described.

DESCRIPTION

FIG. 1 is a perspective view of a knob showing our new design.

FIG. 2 is a top view of FIG. 1;

FIG. 3 is an end view of FIG. 1;

FIG. 4 is a right second side view of FIG. 1, the left side being a mirror image of FIG. 4;

FIG. 5 is another end view of FIG. 1;

FIG. 6 is a bottom view of FIG. 1; and,

FIG. 7 is a cross-sectional view of FIG. 2 taken along line 7—7.

The ornamental design which is claimed is shown in solid lines in the drawings. The broken lines in the drawings are for illustrative purposes only and form no part of the claimed design.
